UNITED STATES PATENT OFFICE.

ALBERT E. BAUM, OF WATERLOO, IOWA, ASSIGNOR OF ONE-HALF TO
AUGUST SCHOEL, OF WATERLOO, IOWA.

DOUGHNUT-CUTTER.

SPECIFICATION forming part of Letters Patent No. 788,698, dated May 2, 1905.

Application filed June 7, 1904. Serial No. 211,480.

To all whom it may concern:

Be it known that I, ALBERT E. BAUM, a citizen of the United States of America, and a resident of Waterloo, Blackhawk county, 5 Iowa, have invented certain new and useful Improvements in Doughnut-Cutters, of which the following is a specification.

My invention relates to improvements in doughnut-cutters; and the object of my invention is to provide means whereby dough may be shaped into the required configuration and portions thereof cut from the original mass and without interference therewith dropped into the receptacle placed to receive them. 10 This object I have accomplished by the means which are hereinafter described and claimed and which are illustrated in the drawings hereto annexed, and in which—

Figure 1 is a side elevation of my improved cake-cutter. Fig. 2 is an end elevation thereof. Fig. 3 is a bottom plan view thereof, and Fig. 4 is a detail view of the cam and reciprocating mechanism.

Horizontally-disposed corrugated drums *b* and *c* are mounted parallel, to each other on the shafts *k'* and *l'*, pivoted in bearings within and between the side plates *d* and *e* of the machine. These drums are caused to rotate inwardly toward each other by means of the 25 intermeshing gears *k*, *m*, and *l*, the pinions *n* and *o*, and the crank *p*. The pinion *n* is mounted upon a short shaft *n'*, pivoted in one end of an adjustable slide-piece *s*, the latter being slotted lengthwise and movable longitudinally on a bolt *s'*, which is screwed into the stud *d'*. The pinion *n* intermeshes with the teeth of the gear *m*, the latter being fixed upon the same shaft *k'* to which the gear *k* is keyed. The shaft *o'* of the pinion *o* extends 30 through bearings in the side plates *d* and *e* and is furnished with a bevel-gear *q*, with which the bevel-pinion *r* intermeshes. The shaft *t* of the pinion *r* is rotatable within bearings in the brackets *e'* and *e''* and has at 35 its lower end a cam-wheel *u*, whose lower surface has a pin *u'*. A hook *x* rests upon the upper surface of the cam-wheel *u*, and its long arm is ridden by a fork *x'*, whose inner end has its upwardly-extending stud *x''* pivoted to

a stud on the bracket *e'*. The stud *u'* on the 50 cam-wheel *u* extends downwardly into and works within a longitudinal slot in the fork *x'*. At the end of the long arm of the hook *x* is placed an upward-extending block *x''*, to which is fixed one end of a bow *w*, carrying 55 a wire cutter *w'*. The spring *v*, whose ends are fastened and held between the nuts *j* and plates *i*, extends downwardly and contacts with the upper surface of the block *x''*. The bottom plate *h* carries a downwardly-extending hollow truncated cone *f*, within which a die *f'* is mounted on the supports *f''*. A hopper *a* is mounted between the upper portions 60 of the side plates *d* and *e*.

The machine is suspended from a bracket *z'* by means of a horizontally-movable arm *z*, pivoted between said bracket and its lugs *e'*. A handle *y* is pivoted between the outwardly-extending lugs *d'* and *e'* on the side plates *d* and *e*. 70

When in use, the machine may be guided over any portion of a pan placed beneath it by means of the handle *y*. When a supply of dough has been placed in the hopper *a* and the crank *p* is turned, the corrugated surfaces 75 of the drums *b* and *c* catch and draw it down between them and force it into a compartment contained between the side plates *d* and *e* and the slanting end plates *g*. The upper edges of the end plates *g* nearly approach the 80 surfaces of the corrugated drums *b* and *c*, and thus act as scrapers, keeping the dough from exuding from the containing-chamber. The said end plates are made removable for the purpose of cleaning and when in place are 85 retained by means of the hooks *g'* connected thereto, which engage the projections *h'* of the bottom plate *h*. The dough being under compression in said compartment is forced downward between the die *f'* and hollow truncated cone *f*, where it acquires the desired 90 configuration. The rotation of the crank *p* causes the bevel-gear to rotate the cam-wheel *u*. The stud *u'* working within the slot in the fork *x'* causes said fork to move on its 95 pivot *x''*, and with it the hook *x*. The bow *w* and its cutter *w'* are thus reciprocated across the lower surface of the cone *f*. The spring

v prevents the cutter *w'* from contacting with the cone *f*. The short arm of the hook *x* rides upon the upper part of the cam-wheel *u*. This short arm moves upon and is supported by the higher part of the cam-surface during that part of the latter's revolution when the cutter *w'* is being horizontally reciprocated over and close to the lower surface of the cone *f*. As a result of the continued revolution of the cam-wheel *u*, as shown in Fig. 4, the short arm of the hook *x* drops to the lower portion of the cam, which results in a lowering of the block *x³* with its bow *w* and cutter *w'*. This position of the cutter is maintained during that portion of the revolution of the cam-wheel *u* where said cutter is being reciprocated back to its first position. This dropping of the cutter *w'* during its return movement is necessary in order to prevent its coming in contact with the dough extending through the cone *f*. As the cutter *w'* cuts off a portion of the dough said portion drops edgewise into the hot grease in the pan, and a slight displacement of the position of the machine puts it into a new position for the deposition of a fresh portion.

This machine is constructed in the above-described method and suspended on a bracket-hanger in order to particularly adapt it for use in cutting and dropping doughnuts into the pans of boiling grease set thereunder. It is well known that if such portions of dough are placed in a pan and the grease poured over them the cakes will stick to the bottom of the pan and burn there, and, on the other hand, if the cakes are first powdered with flour before being deposited in the pan the flour burns and covers the cakes with an unsightly coating. The machine which is hereinbefore described is the only one which can obviate either of the said objections, inasmuch as it cuts off the portions and drops them directly into the boiling grease in the pan without the necessity for a powdering of flour, and by reason of the adjustable hanger enables the machine to be shifted from side to

side until the surface of the grease is filled. As the cakes drop into the hot grease they first sink, then as the heat develops gases within their inner structure they arise to the top, are cooked, and may be removed.

While I am aware that machines have been constructed which will sever portions of a viscous substance and drop them on a receptacle or carrying-surface, yet I maintain that for the proper deposition of the portions of dough cut off for doughnuts and their regular distribution and submergence in the boiling grease underneath the combination of elements shown accomplish a new and useful function and one attainable in no other way.

Having described my invention, what I claim as new, and desire to secure by Letters Patent, is—

1. A doughnut-cutter, consisting of a die, means for forcing dough therethrough, a cam-wheel, means for rotating said cam-wheel, a reciprocating cutter, means whereby said cam-wheel may reciprocate said cutter close to the surface of said die on its cutting stroke and farther away therefrom on its return stroke, and means for varying the position of the whole machine, substantially as shown and described.

2. A doughnut-cutter, consisting of a frame, a die therein, corrugated drums mounted over said die adapted to force dough therethrough, means for rotating said drums, a cam-wheel, means for rotating said cam-wheel, a reciprocating cutter, means whereby said cam-wheel may reciprocate said cutter close to the surface of said die on its cutting stroke and farther away therefrom on its return stroke, and means for varying the position of the whole machine, substantially as shown and described.

Signed at Waterloo, Iowa, this 1st day of June, 1904.

ALBERT E. BAUM.
